UNITED STATES PATENT OFFICE

ELI MAYNARD LONG, OF GENEVA, NEW YORK, ASSIGNOR TO SHUR-ON STANDARD OPTICAL COMPANY, INCORPORATED, OF GENEVA, NEW YORK, A CORPORATION OF NEW YORK

LENS GRINDING AND POLISHING MACHINE

Application filed March 12, 1925. Serial No. 14,964.

This invention relates to a machine for grinding and polishing the surfaces of toric lenses and other objects having analogous surfaces but may be used in other relations in which an abrasive element and a work holding element are reciprocally movable one in relation to the other within predetermined limits hereinafter defined as the "field" of movement of the movable element. The main object is to provide simple and efficient means for automatically changing the relative motion between the work and polishing or grinding surface at different positions during progressive grinding or polishing for the purpose of breaking up the continuity of any error or imperfection which may exist in the grinding or polishing surface.

In other words, I have sought to produce a continuous change of the field of movement of the moving element during each cycle of reciprocal operation as the grinding or polishing progresses and thereby to reduce to a minimum the liability of scoring of the lens by slight imperfections or errors in the grinding surface.

Another object is to operate the means for changing the field of action of the movable element by a part of the same means which is employed for reciprocating said element and thereby to compound the reciprocal motions of the moving element by a single driving connection between the driving and driven elements. One of the specific objects is to effect a continuous variation in the amplitude of reciprocation of one of the grinding elements as distinguished from an intermittent variation of amplitude.

Other objects and uses relating to specific parts of the device will be brought out in the following description.

In the drawings:

Figure 1 is a transverse vertical sectional view, partly in elevation, of a lens grinding and polishing machine embodying the features of my invention.

Figure 2 is a sectional view taken in the plane of line 2-2, Figure 1 looking toward the right hand but showing the bracket or connecting rod mainly in elevation.

Figure 3 is a diagrammatic view of the means for operating the movable lens-supporting element across the grinding face and indicating by full lines the two extreme positions of said movable element under certain predetermined adjustments. 55

In order that the invention may be clearly understood I have shown a portion of a frame or housing —1— carrying a suitable lap or grinding element —2— preferably on the front side thereof and in fixed relation thereto.

The bottom of the case or housing —1— is provided with one or more upstanding posts —3— upon which a frame —4— is pivoted on the shaft —5— for vertical rocking movement. 65

The front and rear ends of the frame —4— are provided with trunnions —6— to which is pivotally connected a yoke —7— for lateral 70 rocking movement about an axis at right angles to the axis of the pivot —5—.

This yoke —7— carries at its upper end a pivot or pivots —8— to which is pivoted intermediate its ends an additional frame 75 —9— for vertical rocking movement about an axis parallel with the axis of the pivot —5—. This upper frame —9— is provided with front and rear end trunnions —10— to which is pivoted a superposed frame —11— 80 which extends through an opening —12— in the front end of the case above the lap —2— and carries a pin —13— adapted to engage an underlying lens-holder —14—, the trunnions —10— being parallel with the axis of 85 the trunnions —6— and, therefore, at right angles to the axes of the pivots —5— and —8—.

The lens or lenses to be ground may be fastened in any suitable manner to the under-side of the lens-holder —14— for reciprocal movement across and upon the upper face of the lap —2— for grinding or polishing purposes as the frame —4— carrying the yoke —7— and supplemental frames —9— and 95 —11— are reciprocated forwardly and rearwardly about the axis of the pivot —5—, in a manner hereinafter described.

The extension as —11'— of the frame —11— may be weighted or otherwise pressed 100

toward the lap —2— to exert corresponding pressure upon the lens-holder —14— and thereby to hold the lens in contact with the grinding element —2—.

5 The parts thus far described may be of any suitable construction capable of imparting a forward and rearward reciprocal motion to the lens-holder —14— and lenses carried thereby and, therefore I do not wish to 10 limit the invention to such construction.

15 The oscillatory frame or carriage —4— is shown as provided with an upwardly projecting boss —15— having a lengthwise aperture —16— in which is secured one end of a curved arm —18— concentric with and having its center of curvature approximately in the axis of the driving element presently described.

20 A rotary driving shaft —19— is journaled in the upper rear portion of the case —1— transversely thereof and preferably at the rear of the supplemental frames —9— and —10— and is provided at one end with a reduced eccentric extension —20— carrying 25 a worm —21— and one end of a connecting rod or bracket —22— having its lower end adapted to receive and support a laterally extending stud or bearing —23—, the intermediate portion —24— of said connecting rod being tubular for receiving a rotary shaft —25—. The shaft 19 may be driven by any suitable means, not necessary to here illustrate or describe.

30 The upper end of the bracket —22— is 35 provided with an off-set extension —26— having a journal bearing —27— for the eccentric extension —20— to permit the latter to rotate freely therein between the hub of the worm —21— and enlarged portion of the 40 shaft —19— which serves to hold the upper end of the bracket —22— against axial movement on the extension —20—.

45 The lower end of the connecting rod —22— is provided with a lateral extension —28— carrying a hub —29— in which the adjacent end of the stud —23— is firmly secured. The shaft —25— is journaled in the tubular intermediate portion —24— of the connecting rod —22— and has its upper end provided 50 with a worm gear —30— meshing with the worm —21— for receiving relatively slow motion therefrom.

55 The lower end of the shaft —25— is provided with a worm —31— meshing with a worm gear —32— which is journaled on the stud —23— and is provided at one end with a 60 axially extending eccentric cylindrical hub —33— which together with the gear —31— are rotatably mounted on the stud —23— between the hub —29— of the extension —28— and shoulder —34— on the opposite end of the stud —23— to hold the gear —32— and its eccentric hub —33— against axial movement on the stud.

65 A yoke —35— is journaled on the eccentric

hub —33— of the gear —32— and is provided with an aperture —36— for receiving the curved arm —18— and permitting said yoke to be adjusted to different positions along and upon said arm, the yoke —35— being 70 provided with a set screw —37— by which it may be clamped to the arm —18— in any position of adjustment.

75 As previously stated the center of curvature of the arm —18— is in or near the axis of rotation of the shaft —19— and, therefore, the connecting rod or bracket —22— may be freely adjusted along said arm about the axis of the driving shaft for varying the reciprocal movement of the lens-holder and 80 lens thereon across the face of the lap —2— through the medium of the connections —4—, —7—, —9— and —11—.

85 For example, the eccentric extension —20— of the shaft —19— has a fixed throw which is transmitted through the connecting rod —22—, stud —23—, eccentric —33— and yoke —35— to the arm —18— and thence through said arm to the parts —4—, —7—, —9— and —11— and thence to the work 90 holder —14— and it, therefore, follows that the adjustment of the yoke —35— nearer to or farther from the axis of the pivot —5— of the frame —4— will correspondingly increase or diminish the amount of reciprocal 95 movement of the lens-holder across the face of the lap.

100 It will be noted, however, that during this major reciprocal movement, the eccentric —33— is being continuously rotated at a very much slower rate of speed than that of the shaft —19— which causes an independent movement of the yoke —35— and arm —16— to which it is secured in the direction of length of the connecting rod —22— and this 105 independent movement is transmitted to the lens-holder —14— and lens carried thereby through the medium of the parts —4—, —7—, —9— and —11—.

110 In other words, the yoke —35— is carried eccentrically around the axis of the stud —23— as the latter is reciprocated vertically by the eccentric extension —20— of the main shaft —19— through the medium of the connecting rod or bracket —22— thereby 115 causing a continually varying effective length of the connection between the driving shaft —19— and arm —18— which in turn causes a continually changing scope and field of action of the lens-holder and lens carried thereby across the grinding surface of the lap —2— through the medium of the parts —4—, —7—, —9— and —11—.

120 This continually varying scope and field 125 of movement of the lens across the surface of the grinder reduces to a minimum the liability of scoring or otherwise injuring the lens by any slight imperfections or errors which may exist in the grinding or polish- 130

ing surface and thereby carries out the main object of the invention.

In the diagrammatic view shown in Figure 3 the part —19— represents the driving shaft while the parts —20— represent the eccentric extension in different positions 90 degrees apart.

The lines —22— represent the connecting rod or bracket in its extreme upper and lower positions as produced by the corresponding positions of the eccentric extension —20— while the points —23— represent the upper and lower positions of the stud —23— as produced by the corresponding positions of the lines —22— so that the distance between the points —23— represent the maximum throw of the eccentric extension —20— when the yoke —35— is in the position shown.

It will be evident however from the previous explanation that during this movement of the stud —23— through the medium of the connection —22— the eccentric —33— is being slowly rotated about the axis of the stud and effects a corresponding eccentric movement of the yoke —35— which latter movement is transmitted by said yoke to the arm —18— thereby varying the position of said arm relatively to the stud —23— and axis of the eccentric extension —20— of the main driving shaft —19— and effecting a corresponding gradual lengthening or shortening of the effective distance between the axis of the eccentric extension —20— and axis of the arm —18— at its point of connection with the yoke —35— and causing said arm to move through gradually varying distances within the limits shown by the full lines —18—, Figure 3.

For example, assuming that the stud —23— has been moved to its extreme up position by the eccentric —20— through the medium of the connecting rod —22— and that while at that position the high point of the eccentric —23— is directly over the axis of the stud —23— then the point of connection between the arm —18— and yoke —35— will assume a position as —a—, Figure 3, above the stud —23— equal to the radius of throw of the eccentric as indicated by the circular line —a'—, Figure 3, thereby amplifying the movement of the arm —18— and lens holder actuated thereby to that extent.

Again assuming that the stud —23— has been moved to its lowest position by the eccentric —20— through the medium of the connecting rod —22— as shown in Figure 3 and that the high point of the eccentric —33— is directly below the axis of the stud —23— then the point of connection between the arm —18— and yoke —35— will have been moved a corresponding distance below the stud —23— at its lower position shown in Figure 3 thereby further amplifying the movement of the arm —18— and lens holder actuated thereby.

It will be observed however that owing to the driving connections between the main shaft —19— and eccentric —33— and relative slow speed of rotation of the eccentric extension —20— the position of the point of connection between the arm —18— and yoke —35— is continually but slowly changing and that at every change of this point the stud —23— is being reciprocated a distance corresponding to the throw of the eccentric extension —20— thereby causing the arm —18— and lens holder actuated thereby to travel through continually changing paths or fields of action which reduces to a minimum the liability of scoring or otherwise injuring the lens by any errors or imperfections in the grinding surface of the lap during progressive grinding or polishing.

I claim:

1. In a lens grinding and polishing machine of the character described, a grinding element and a lens holding element, a rotary eccentric and a support therefor, means for reciprocating the support with the eccentric thereon at right angles to the axis of rotation of the eccentric, means for continuously rotating the eccentric during its reciprocation, and means actuated by the combined reciprocal and eccentric motion of the eccentric for reciprocating one of said elements relatively to the other element.

2. In a lens grinding and polishing machine of the character described, a grinding element and a lens holding element, a rotary driving member having an eccentric bearing, a rock-arm, connections for transmitting motion from the eccentric bearing to the rock-arm including means for continuously varying the distance between the points of connection of said connections with the eccentric bearing and rock-arm as the bearing is rotated, and means for transmitting motion from the rock-arm to one of said elements.

3. In a lens grinding and polishing machine of the character described, a grinding element and a lens holding element, a rotary driving member having an eccentric bearing, a connecting rod journaled on said bearing member, a rotary eccentric carried by said connecting rod, means for transmitting continuously rotary motion from said driving member to the eccentric, a yoke journaled on the eccentric to be reciprocated thereby and by the connecting rod, and means for transmitting motion from said yoke to one of said elements.

4. In a lens grinding and polishing machine of the character described, a grinding element and a lens holding element, a rotary driving member having an eccentric bearing, a connecting rod journaled on said bearing for reciprocal movement as the eccentric bearing is rotated, a stud carried by said rod, a rotary eccentric journaled on said stud, means for transmitting continuously rotary motion

from the driving member to the eccentric, a yoke journaled on the eccentric for reciprocation thereby and by the connecting rod, and means for transmitting the combined reciprocal movements of the yoke to one of said elements.

5. In a lens grinding and polishing machine, a grinding element, a lens-holding element, means including a pivoted frame for 10 supporting and reciprocating one of said elements, a rotary eccentric, an arm secured to the frame and having a curved portion substantially concentric with the axis of rotation of the eccentric, and means actuated by said 15 eccentric and operatively connected to said arm for rocking said frame on its pivot, the connection of the last-named means with the arms being adjustable lengthwise of the curved portion of the arm to vary the amplitude 20 of oscillation of the frame and thereby to vary the stroke of the element carried thereby.

In witness whereof I have hereunto set my hand this third day of March 1925.
